BED-MOTION FOR PRINTING-MACHINES.

1,214,102.

Specification of Letters Patent. Patented Jan. 30, 1917.

Application filed August 6, 1915. Serial No. 43,903.

To all whom it may concern:

Be it known that I, BRUCE C. WHITE, a citizen of the United States, residing at New York city, county of New York, and State of New York, have invented certain new and useful Improvements in Bed-Motions for Printing-Machines, fully described and represented in the following specification and the accompanying drawings, forming a part of the same.

This invention relates particularly to bed motions for bed and cylinder printing machines, and especially to that class of machines in which the bed is driven during the main part of its stroke through rack and gear mechanism, and at the end of its stroke in either direction is controlled and actuated by levers brought into engagement with the bed.

The especial object of the invention is to provide a simple, efficient and durable mechanism by which the proper motion of the bed shall be secured, especially in reversing the movement of the bed at each end of its stroke so as to secure a smooth and easy movement of the bed in these parts of its movement, while at the same time permitting a simple, compact and low press frame.

For a full understanding of the invention, a detailed description of a construction embodying the same in its preferred form will now be given in connection with the accompanying drawings forming a part of this specification, and the features forming this invention then specifically pointed out in the claims.

In the drawings—Figures 1, 2, 3 and 4 are vertical sections taken inside the frame, showing the press in different positions of the bed. Fig. 5 is a reversed plan view of the bed rack.

Referring to the drawings, A is the cylinder and B the bed of a bed and cylinder printing machine, the bed B sliding on frame C in ways D, and carrying on its under side the rack E, as usual in such constructions, a single central rack being used in the machine shown as the preferred embodiment of my invention.

Referring now to the bed driving mechanism, the bed is driven through the main portion of its movement in opposite directions by two gears 10, 11, rotating in oppo-

site directions, and shown as meshing together, these gears engaging the rack E alternately, and for this purpose being mounted on a frame 12 mounted to rock on pivot shaft 13 and carrying an arm 14 having a bowl 15 running in the cam groove 16 on cam disk 17, this cam acting to rock the frame and raise and lower the gears 10, 11, alternately. Each of the gears 10, 11 is cut away through a portion of its face circumferentially and widthwise, so as to form a gap *a* extending partially across the tooth face of the gear, and the rack E is provided at opposite ends with coextensive and corresponding gaps *b* extending partially across the face of the rack, the gaps *a*, *b* being upon opposite sides of the gears and rack, so that when a gear gap registers with a rack gap, the gear does not mesh with the rack, although in its raised meshing position.

The bed is controlled and driven at the opposite ends of its stroke, independently of the gears 10, 11, by levers 18, 19 provided with bowls 1 at their upper ends which engage bearing notches 2 formed in brackets 20 secured on the lower side of the bed frame, the levers 18, 19 preferably being double, or formed of two bars carrying the bowls 1 between them, although this is not essential. Separate brackets and bearing notches for the two levers 18, 19 are used in the construction illustrated, but it will be understood that this is not essential, but that a single bearing notch may be used for the two levers. The levers 18, 19 have movable fulcra permitting the upward and downward movement of the levers, these fulcra being formed by the swinging links 21 pivoted to the frame at 22, and in the outer ends of which the levers are pivoted. The levers 18, 19, are actuated by crank rods 23 from crank pins 5 carried by gears 10, 11, these crank rods being pivoted to the levers at 25.

The control of the levers 18, 19 to secure the upward and downward movement of the bowls 1 on the swinging levers to engage and release the bed and the substantially horizontal movement of the bowls 1 parallel with the bed during that portion of their movement when in control of the bed, and especially in stopping and reversing the bed, is secured by the following means: Each of

the levers 18, 19 is suspended from the bed frame by a link 24 swinging freely on the frame and lever. These levers 18, 19, fulcrum links 21 and crank rods 23, are arranged so as to form a parallel movement device, by which the bowls 1 of levers 18, 19 move upward and downward as the levers swing to enter and leave the notches 2 on brackets 20, and move substantially horizontally or parallel with the bed during the main bed controlling movement, and the pivots 25 of the levers and crank rods move substantially in a straight line, which, with the gear and crank movement shown, intersects the center of the point 13 of the rocking gear frame 14.

The parts above described may be driven in any suitable manner to secure the desired timing, and their operation will be understood from a brief description in connection with the positions of the parts shown in the drawings.

As shown in Fig. 1, the bed B is just coming into printing position on its movement 25 to the right, being driven by gear 10 after being released by lever 18. As the bed completes its printing movement to the right and approaches the end of its stroke, the lever 19 is rocked by crank rod 23 from gear 11, so as to move the lever outward or to the right, swinging on links 24, 21, and on this movement the bowl 1 is first raised into notch 2 on the right hand bracket 20, and then the bowl 1 is moved substantially parallel with the bed during the further outward movement of lever 19, and especially at the time of stopping and reversing the bed. The gear 10 is shown in Fig. 2 as just completing its bed driving movement, and the gears 10, 11 are to be shifted by the cam groove 16 to lower gear 10 and raise gear 11 for the return stroke. As gear 10 closes its bed driving movement, lever 19 is moved outward from the position shown in Fig. 2, and takes control of the bed, retards it gradually to a stop at the end of its stroke, reverses it, and gradually accelerates its speed up to the speed of the gears 10, 11, and bowl 1 on lever 19 is then lowered from notch 2, friction from upward and downward movement of the bowl 1 in notch 2 during the control of the bed by the lever being avoided by the movement of the bowl parallel to the bed secured by the link motion shown. The same operation is repeated with lever 18 at the end of the movement of the bed to the left, the position of the parts as the bed approaches the end of its movement and is engaged by the lever 18, and after the reversal of the bed as the lever 18 is advancing it into position to be taken by gear 10, being shown, respectively, in Figs. 3 and 4. In Fig. 4 it will be seen that gear 10 is just being raised for meshing with 65 rack E but with gaps *a*, *b* opposite each

other, so that the gear and rack will not mesh until the ends of the gaps are reached and the gear and rack are brought into mesh by the longitudinal movement of the bed.

The action of the link movement will be 70 clear from Fig. 4, which shows the position of extreme bed movement, with the gears half rocked and the crank pins in their extreme positions in one direction. The rocking of the gear frame 12 is the same in degree and time in both directions from the 75 position of Fig. 4, and from this position the pivots 25 move in straight lines which pass through the center of pivot 13, this result being secured by the link movement and 80 resulting in the proper movement of the bowl 1.

The gaps *a*, *b* on gear 11 and rack E provide for raising the gear into position where the gear and rack will mesh at the inner ends 85 of the gaps, so that the bed rack in its travel moves into mesh with the gear 11 at the end of the gap, instead of the gear being raised to bring its teeth into mesh during the movement of the bed. This gap action is preferably used as avoiding all danger of injury 90 to the teeth, which would result from incorrect position in bringing them into mesh by vertical movement, and shortens the movement of the bed, as compared with constructions in which the rack runs beyond 95 both gears before they are shifted, but these gaps in the gears and racks may be omitted.

The movement of the bowls in a horizontal line parallel with the movement of the bed during the control of the bed by the levers, not only avoids friction and wear on the bowls and bed and secures the desired accurate printing registry, but also secures the important result of avoiding upthrust or downthrust upon the bed, which otherwise is liable to produce vertical movement of the bed at the time of heaviest pressure on the bowls in controlling or moving the bed, and in any case increasing the friction 100 load and inducing a rocking action in the bed motion. Uniformity of speed in moving the bed in both directions is secured, also, the pivot pins in the connecting rods traveling in a line horizontal and parallel with the 105 movement of the bed, whether the crank pin is below or above the center line, so that the levers pick up the bed from the rack motion at exactly the rack speed and deliver the bed to the rack motion at exactly rack 110 speed.

While the two oppositely rotating gears alternately engaging a single rack on the bed are preferably used for driving the bed during the main portion of its movement, 115 and the combination of this mechanism with my improved means for reversing the bed forms a specific part of the invention, it will be understood that my improved reversing means may be used with other com- 120 125 130

mon or suitable means for driving the bed during the main portion of its movement, and such combinations are included within the invention.

5 While the invention is especially intended for bed and cylinder printing machines, it will be understood that it may be applied also to other machines employing a bed or similar member making a rapid reciprocation and requiring to be reversed at one or both ends of its stroke in a manner similar to the type beds of printing machines, and the term "type bed" is intended to include such other beds or similar reciprocating members. It will be understood, also, that the invention is not to be limited to the particular construction or arrangement shown, but that other arrangements may be used while retaining the invention defined by the 10 claims.

20 What I claim is:

1. The combination with a reciprocating bed and means for driving it during the intermediate portion of its movement in either 25 direction, of rocking levers acting to retard, stop, reverse, and accelerate the bed at the ends of its movement, means for rocking said levers, and link supports for said levers, said link supports being arranged to 30 raise and lower the levers during the rocking movement to engage and release the bed and to secure the movement of the bed engaging part of the levers in substantially a straight line parallel with the bed movement, except at the beginning and end of 35 their bed engaging movement.

2. The combination with a reciprocating bed and means for driving it during the intermediate portion of its movement in either 40 direction, of rocking levers acting to retard, stop, reverse and accelerate the bed at the ends of its movement, crank mechanism for rocking said levers, and link supports for said levers, said link supports being arranged to 45 raise and lower the levers during the rocking movement to engage and release the bed and to secure the movement of the bed engaging part of the levers in substantially a straight line parallel with the bed movement, except at the beginning and end of 50 their bed engaging movement.

3. The combination with a reciprocating bed, of rocking levers acting to retard, stop, reverse, and accelerate the bed at the ends 55 of its movement, cranks and connections for rocking said levers, bed driving gears for moving the bed in opposite directions, means for engaging and releasing the bed with and from said gears alternately, and link supports for said levers, said link supports being arranged to raise and lower the levers during the rocking movement to engage and release the bed and to secure the movement of the bed engaging part of the levers in 60 substantially a straight line parallel with 65

the bed movement, except at the beginning and end of their bed engaging movement.

4. The combination with a reciprocating bed, of rocking levers acting to retard, stop, reverse, and accelerate the bed at the ends 70 of its movement, cranks and connections for rocking said levers, bed driving gears for moving the bed in opposite directions, a single rack on the bed, a rocking frame carrying said gears, means for rocking said frame to move said gears alternately into and out of mesh with the rack, said racks and gears having gaps extending across a part of their width and arranged on opposite sides of the rack and gears, whereby the 75 gears may be brought into meshing position without engagement of the rack and gear teeth until the ends of the gaps are reached in the movement of the bed, and link supports for said levers arranged to raise and 80 lower the levers during the rocking movement to engage and release the bed and to secure the movement of the bed engaging part of the levers in substantially a straight line parallel with the bed movement, except 85 at the beginning and end of their bed engaging movement.

5. The combination with a reciprocating bed and means for driving it during the intermediate portion of its movement in 90 either direction, of rocking levers acting to retard, stop, reverse, and accelerate the bed at the ends of its movement, said levers having fulcra movable transversely to the bed, means for rocking said levers, and a 95 swinging connection between the levers and the frame arranged to secure the raising and lowering of the levers on their movable fulcra during the rocking movement to engage and release the bed and to secure the movement of the bed engaging part of the levers in substantially a straight line parallel with the bed movement, except at the beginning and end of their bed engaging movement.

6. The combination with a reciprocating bed and means for driving the bed during the intermediate portion of its movement including gear wheel 10, of bearing notch 2 on the bed, lever 18 having bowl 1 for engaging said bearing notch, swinging link 21 on which said lever is mounted, a crank pin on wheel 10 and its connecting rod 23 connected to the lever by pivot 25 for rocking said lever, and link 24 controlling the lever 115 to cause the pivot 25 to travel in a horizontal line parallel with the movement of the bed, substantially as described.

7. The combination with a reciprocating bed having rack E, of bearing notch 2 on 120 the bed, lever 18 having bowl 1 for engaging said bearing notch, swinging link 21 on which said lever is mounted, gear wheel 10 and connecting rod 23 connected to the lever by pivot 25 for rocking said lever, rocking 125 130

- frame 12 carrying gear 10 and having pivot 13, and link 24 controlling the lever to cause the pivot 25 to travel in a horizontal line parallel with the movement of the bed and 5 at the same vertical distance from the rack as the center of pivot 13, substantially as described.
8. The combination with a reciprocating bed having rack E, of oppositely rotating gears 10, 11 for driving the bed, rocking frame 12 carrying said gears and having pivot 13, a cam for rocking said frame to alternately move said gears into and out of meshing position with the rack, rocking levers 18, 19, a crank pin on each gear, connecting rods 23 connected to said crank pins and to said levers by pivots 25, swinging links 21 on which the levers are mounted, and links 24 controlling the levers to cause 10 the pivots 25 to travel in a horizontal line parallel with the movement of the bed and at the same vertical distance from the rack as the center of pivot 13, substantially as described.
9. The combination with a reciprocating bed and means for driving it during the intermediate portion of its movement in either direction, of rocking levers acting to retard, stop, reverse, and accelerate the bed at the 15 ends of its movement, means for rocking said levers, and means coacting with said levers to raise and lower the levers during the rocking movement to engage and release the bed and to secure the movement of the bed engaging part of the levers in substantially a straight line parallel with the bed movement, except at the beginning and end of their bed engaging movement.
10. The combination with a reciprocating bed and means for driving it during the intermediate portion of its movement in either direction, of rocking levers acting to retard, stop, reverse and accelerate the bed at the 20 ends of its movement, crank mechanism for rocking said levers, and means coacting with said levers to raise and lower the levers during the rocking movement to engage and release the bed and to secure the movement of the bed engaging part of the levers in substantially a straight line parallel with the bed movement, except at the beginning and end of their bed engaging movement.
11. The combination with a reciprocating bed, of rocking levers acting to retard, stop, reverse, and accelerate the bed at the ends 25 of its movement, cranks and connections for moving the bed in opposite directions, means for engaging and releasing the bed with and from said gears alternately, and means coacting with said levers to raise and lower the levers during the rocking movement to engage and release the bed and to secure the movement of the bed engaging part of the levers in substantially a straight line parallel with the bed movement, except at the beginning and end of their bed engaging movement.
12. The combination with a reciprocating bed, of rocking levers acting to retard, stop, reverse, and accelerate the bed at the ends of its movement, said levers having fulcrum 30 movable transversely to the bed, cranks and connections for rocking said levers, means for raising and lowering said levers to engage and release the bed, bed driving gears rotating with said cranks for moving the bed in opposite directions, a single rack on the bed, a rocking frame carrying said gears, and means for rocking said frame to move said gears alternately into and out of mesh with the rack.
13. The combination with a reciprocating bed, of rocking levers acting to retard, stop, reverse, and accelerate the bed at the ends of its movement, said levers having fulcrum 35 movable transversely to the bed, cranks and connections for rocking said levers, means for raising and lowering said levers to engage and release the bed, bed driving gears rotating with said cranks for moving the bed in opposite directions, a single rack on the bed, a rocking frame carrying said gears, and means for rocking said frame to move said gears alternately into and out of mesh with the rack, said racks and gears having gaps extending across a part of their width and arranged on opposite sides of the rack and gears, whereby the gears may be brought 40 into meshing position without engagement of the rack and gear teeth until the ends of the gaps are reached in the movement of the bed.
14. The combination with a reciprocating bed having a rack, of two gears rotating in opposite directions, means for moving the gears into and out of mesh with the rack alternately, a gap at each end of the rack extending across a part of its width, a gap in each gear co-extensive with the length of the 45 gap in the rack and occupying the ungapped part of the width of the rack, whereby the teeth of the gears will be out of engagement with the teeth of the rack when the gaps are opposite each other.
15. The combination with a reciprocating bed having a rack, of two equal oppositely rotating gears engaging the rack alternately, a crank pin on each gear, a pair of rocking levers, a connecting rod from each crank pin 50 to one of the levers, one of said levers engaging the bed when the latter is near the end of its travel in one direction to continue its movement at the same speed as when engaged by the gear, then retard the movement of the bed and stop it, then reverse the movement of the bed and accelerate it until it has reached a speed equal to the peripheral speed of the gear, then move the bed back into engagement with said gears, said lever at the 55

same time moving out of engagement with the bed, the other of said levers engaging the printing bed at the end of its travel in the opposite direction to similarly reverse its movement, and means for actuating said gears and levers.

16. The combination with a reciprocating bed having rack E, of oppositely rotating gears 10, 11, for driving the bed, a rocking frame carrying said gears, a cam for rocking said frame to alternately move said gears into and out of meshing position with the rack, rocking levers 18, 19, a crank pin on each gear connected to one of said levers, and means for engaging and disengaging said levers with and from the bed during the rocking movement of the levers.

17. The combination with a reciprocating bed having rack E formed with gaps b at

opposite ends extending across a portion of 20 the width of the rack, of oppositely rotating gears 10, 11 having gaps a extending across a portion of the width of the gear on the opposite side of the gears from the rack gaps 25 b, means for reversing the movement of the bed independently of said gears, and means for moving said gears alternately into and out of meshing position with the rack, and arranged to move the gears alternately into meshing position while the rack and gear 30 gaps are opposite each other.

In testimony whereof, I have hereunto set my hand in the presence of two subscribing witnesses.

BRUCE C. WHITE.
